TRACTION ATTACHMENT FOR WALKING AIDS

Donald L. Speck, Austin, Minn.

Application June 29, 1951, Serial No. 234,420

2 Claims. (Cl. 135—57)

This invention relates to traction grips for walking aids such as crutches and the like.

It has been a problem to provide a relatively inexpensive, yet highly efficient traction attachment for walking aids in the nature of sticks such as crutches, canes and the like which may be quickly and easily attached or removed from the bottom of the stick and which may be conveniently carried in removed or retracted position.

It is an object of my invention to provide an extremely simple and inexpensive, yet highly efficient traction attachment for walking aids such as crutches and the like which may be easily and quickly mounted on the walking aid and may be quickly shifted from retracted to operative position thereon.

It is another object to provide a traction attachment for walking aids which is adapted to be carried on the walking aid in retracted position when not in use and resiliently held in retracted position but constructed to permit quick and easy shifting thereof from retracted position to operative position to resiliently hold the same in operative position on the ground engaging tip of the walking aid.

These and other objects and advantages will more fully appear from the following description made in connection with the accompanying drawings wherein like reference characters refer to the same or similar parts throughout the several views and in which:

Fig. 1 is a side elevational view of one form of my improved traction device for walking aids showing the same in operative position by full lines and in retracted inoperative position by dotted lines;

Fig. 2 is a front elevational view of the structure shown in Fig. 1;

Fig. 3 is a side elevational view of an alternative form of my invention;

Fig. 4 is a rear elevation view of the structure shown in Fig. 3;

Fig. 5 is a bottom plan view of one form of traction plate used in my invention; and

Fig. 6 is a bottom plan view of the traction plate used in another form of my invention.

As illustrated in the accompanying drawings, I show a walking aid such as the crutch 7 having the conventional rubber tip 8 fixed on the bottom thereof.

In Figs. 1, 2 and 6, I show one form of my invention designated by the letter A. In form A, I provide a traction plate 11 having depending pointed teeth 11a and upstanding tab or flange members 11b. The tab members 11b are disposed at the periphery of the plate and extend upwardly from the main body portion thereof to form a tip receiving socket and closely embrace the periphery of the tip 8. In the form shown, two pairs of such tab elements are provided. A pair of attaching members such as resilient elements, respectively designated by the numerals 9 and 10, have one of their ends respectively connected to one pair of said upstanding tab elements in diametrically opposed relation. The upper end of resilient element 10 is hingedly connected to the lower portion of the walking aid as by the screw eye 13. The upper end of the spring 9 is removably attached to detent means such as a hook 15 provided in the lower portion of the crutch 7 on the opposite side thereof from the screw eye 13. A loop 14 forms an interconnection element to facilitate connection between the hook and spring 9. The hook 15 receives the loop or ring 14 to hold the traction plate 11 in operative position with the upper side of the plate

2

engaging the bottom of tip 8 and the tip being received in the socket formed between the upstanding tabs 11b. A second detent or hook 16 is provided to hold the traction plate 11 in upwardly retracted position when not in use, as shown by the dotted line position of Fig. 1, the hook 16 receiving the ring 14. The screw eye 13 forms a hinge or pivot about which the entire traction attachment swings from retracted position into operative position. Two intermediately disposed pivots are also provided at the lower ends of the springs 9 and 10 where said springs are connected with one pair of opposed tab elements 11b.

In the Figs. 3, 4 and 5, an alternative form of my invention is illustrated. A traction plate 12 of quadrilateral shape, such as the rectangular plate illustrated, is provided and has an upwardly projected retaining element 12a adapted to engage the resilient center portion of tip 8 of the walking aid to hold plate 12 against shifting movement. Two rows of teeth 12b are, in the form shown, provided along the side edges of plate 12 in depending relation to the main body portion thereof. A pair of non-resilient links 17 are respectively connected at their lower ends in spaced relation at one end of plate 12 and a pair of screw eyes 18 mounted in the two sides 20 of the walking aid are connected with the upper ends of said links 17 as by the links 19. The two screw eyes 18 provide the hinge about which the plate 12 swings from operative position up into retracted position, as shown by the dotted lines of Fig. 4. A spring 9 identical to the spring 9 of form A having a ring 14 at the upper end thereof is provided and a pair of hooks 15 and 16 respectively hold the plate 12 in operative and retracted positions. An inverted V-shaped link 20 has its lower spaced ends connected with plate 12 and the lower end of spring 9 is connected at the upper end thereof. Obviously the links 17 are of such a length that the plate 12 will be held tightly against the bottom of the crutch tip 8 when the same is in operative position and thus in form B of my invention only a single resilient element is required. The teeth 12b of course serve substantially the same function as the teeth 11a in form A of my invention and prevent slippage of the tip of the walking aid on slippery surfaces.

In both forms A and B of my invention, it will be seen that I have provided highly efficient, easily retractible traction attachments for underlying the conventional tips of walking aids which may be quickly and easily shifted from retraction position into operative position by the user. In form A of my invention as illustrated two resilient retaining elements hold the traction plate 11 in tight engagement with the bottom of tip 8 and in form B of my invention I have found that only a single resilient element is needed since without the upstanding tab members 11b the resiliency of spring 10 is not required and the two non-resilient links 17 may be substituted therefor. These spaced links 17 and V-shaped link 20 engage the lower side portions of the tip 8 and combine with the upwardly extending projection 12a to hold the plate 12 in operative position and prevent lateral, as well as longitudinal, shifting movement thereof.

It will, of course, be understood that various changes may be made in the form, details, arrangement and proportions of the parts without departing from the scope of my invention.

What I claim is:

1. A traction attachment for walking aids in the nature of sticks having conventional resilient traction tips at their lower ends, said attachment comprising a traction plate having a number of depending teeth fixed on the bottom thereof and including upstanding flange means disposed at the periphery of said plate to form a tip receiving socket into which the traction tip of a walking aid is adapted to fit, a pair of resilient elements respectively connected at their lower ends with opposed portions of said flange means, one of said resilient elements being adapted to be hingedly connected to one side of the stick portion of a walking aid in upwardly spaced relation from the lower end thereof and the other being adapted to be releasably connected with the walking aid on the opposite side of the stick portion from said hinged resili-

ient element to hold said traction plate in operative position and on the same side of the stick portion as said hinged resilient element to hold said traction plate in retracted position.

2. A traction attachment for walking aids in the nature of sticks having conventional resilient traction tips at their lower ends, said attachment comprising a traction plate having a number of depending teeth fixed on the bottom thereof and including upstanding flange means disposed at the periphery of said plate to form a tip receiving socket into which the traction tip of a walking aid is adapted to fit, a pair of attaching members, at least one of said members being resilient in nature, respectively connected at their lower ends with opposed portions of said flange means, one of said attaching members being adapted to be hingedly connected to one side of the stick portion of a walking aid in upwardly spaced relation from the lower end thereof and the other being adapted to be

15

releasably connected with the walking aid on the opposite side of the stick portion from said hinged attaching member to hold said traction plate in operative position and on the same side of the stick portion as said hinged attaching member to hold said traction plate in retracted position.
